UNITED STATES PATENT OFFICE.

EDWIN E. MILNER, OF SCOTT TOWNSHIP, AND WILLIAM J. LYCLE, OF ROSSLYN FARMS BOROUGH, ALLEGHENY COUNTY, PENNSYLVANIA, ASSIGNEES TO H. L. DIXON COMPANY, OF CARNEGIE, PENNSYLVANIA, A CORPORATION OF PENNSYLVANIA.

PLATE-GLASS ANNEALING LEER.

1,426,310.

Specification of Letters Patent. Patented Aug. 15, 1922.

Application filed August 16, 1921. Serial No. 492,660.

To all whom it may concern:

Be it known that we, EDWIN E. MILNER, residing at Scott Township, and WILLIAM J. LYCLE, residing at Rosslyn Farms Borough, Allegheny County, Pennsylvania, have invented a new and useful Improvement in Plate-Glass Annealing Leers, of which the following is a full, clear, and exact description.

Our invention relates to plate glass annealing leers and particularly to a muffle leer of the zig-zag type.

An object of our invention is such a device wherein the articles to be handled may be easily and readily introduced into and moved from place to place in the leer.

A further object of our invention is such a device wherein the temperature inside the leer may be accurately controlled.

Further objects and the nature of our invention will be better understood by reading the following description taken in connection with the accompanying drawings forming a part thereof, and in which:

Figure 1 is a view partially in plan and partially in section of a device embodying our invention;

Figure 2 is a cross section on line II—II of Figure 1;

Figure 3 is a section on line III—III of Figure 2;

Figure 4 is a plan view of one of the burners; and

Figure 5 is a section on line V—V of Figure 4.

Referring to the drawings, the device comprises a suitable supporting foundation 1, upon which is constructed the masonry walls 2, carrying a floor 3 of any desirable refractory material. The floor 3 is surrounded by the muffle chamber 4 in which the articles to be treated are placed. The chamber 4 is surrounded by side walls 5 of any suitable material. The top wall of the muffle chamber is composed mainly of a plurality of longitudinally extending flues 6 arranged side by side and extending substantially the full length of the chamber. These flues 6 communicate through headers 7 for the various chambers and the headers 7 are connected by flues 8 with the main flue 9, as best shown in Figure 1. The flue 9 leads to a suitable stack 10 for carrying the products of combustion from the flues. The flues 6 may be formed of any

suitable material such as tile, either of integral construction or built up in separate top and side members as indicated in Figure 3. These flues are supported by I-shaped key blocks 11 shown in section in Figure 3. The key blocks 11 are suspended from channels 12, which are supported by any suitable framework. The top walls of the flues 6 may be reinforced by a layer 13 of brick or other refractory material.

At its front end each of the flues 6 communicates with a vertical combustion chamber 14 which extends upwardly through the one end wall of the muffle chamber. There is a single combustion chamber 14 for all of the flues 6. This combustion chamber 14 is provided with suitable burners 15, shown in detail in Figures 4 and 5. These burners may be used with either producer gas or natural gas. When producer gas is used it is brought into the burner through the flues 16 or tunnel 16 and enters the burner through an opening 17 which is in line with a similar opening 18 in the burner. Air is brought into the burner through the channel 19 and as shown in Figure 4 the air completely surrounds the gas opening 18 in the burner. The flue 16 has an opening for each of the burners so that all of the burners are fed from a common source. If it is desired to vary the amount of gas passing through the burner, the burner may be moved to the right or left as shown in Figure 2, thus placing the openings 17 and 18 slightly out of register so as to cut down the amount of gas supplied.

The device as shown in Figure 1 is provided with an opening 20 through which the plate glass to be annealed is introduced into the furnace. The plates of glass are introduced through the opening 20 on the floor 3. After they have remained in the first compartment A for the required length of time, a suitable tool is introduced through the opening 21 and the plate is moved to the rear of the chamber, after which a similar tool is introduced through the opening 21^a and the plate glass is moved into the chamber B. After the same has remained in that chamber for the required time a tool is introduced through the opening 22 and the plate is moved to the rear of the chamber B and is then moved into the chamber C by a tool introduced through the opening 23 in the

chamber B. From the chamber C the article is carried by any well known means through the cooling chamber D shown broken off in Figure 1. The chamber D may be of any desired length depending upon the circumstances.

In the particular leer shown in the drawings there are twelve of the flues 6 for each of the chambers A, B and C, and each flue is provided with an offtake 24. It will be understood, however, that the number of the flues may be varied according to the size of the leer and that more offtake connections may be provided if desired. The offtake connection may be controlled by any suitable means if desired.

By reason of the arrangement shown, the temperature of the heating chambers may be accurately controlled to produce the desired results. Any desired number of burners 18 may be provided.

The advantages of our invention result from the provision of simple and effective means for heating the article to be annealed and for manipulating and moving that article from place to place through the zig-zag course of the leer in combination with the muffle construction, whereby the article is heated indirectly from a plurality of flues. While we have described our invention in detail, we desire it to be understood that we are not to be limited to the exact arrangement shown, as many changes may be made in the details thereof without departing from the spirit of our invention.

We claim:

1. A plate glass annealing leer having a plurality of heating chambers arranged zig-zag with respect to each other, the upper wall of each of said chambers being formed of a plurality of longitudinally extending heating flues, substantially as described.

2. A plate glass annealing leer having a plurality of muffle heating chambers arranged zig-zag with respect to each other, the upper wall of each of said chambers being formed of a plurality of longitudinally extending heating flues and a common combustion chamber for each flue, substantially as described.

3. A plate glass annealing leer having a plurality of muffle heating chambers arranged zig-zag with respect to each other,

the upper wall of each of said chambers being formed of a plurality of heating flues, 55 a common combustion chamber for each of said flues, and means for producing combustion in said combustion chamber, substantially as described.

4. A plate glass annealing leer having a 60 plurality of muffle chambers arranged zig-zag with respect to each other and a leer in line with the last of said chambers, the top wall of each of said chambers containing a plurality of longitudinally extending heat- 65 ing flues, substantially as described.

5. A plate glass annealing leer having a plurality of muffle chambers arranged zig-zag with respect to each other, a leer in line with the last of said muffle chambers and 70 communicating therewith, the top wall of each of said chambers being provided with a plurality of heating flues and means for heating each of said flues, substantially as described.

6. A plate glass annealing leer having a plurality of muffle chambers arranged zig-zag with respect to each other, the top wall of each of said chambers having therein a plurality of longitudinally extending heat- 80 ing flues and an offtake for each of said flues, substantially as described.

7. A plate glass annealing leer having a plurality of muffle heating chambers arranged zig-zag with respect to each other, a 85 plurality of heating flues in the top wall of each of said chambers, means for producing combustion for each of said flues, and means common to all of said combustion producing means in the side wall of each of said chambers, substantially as described.

8. A plate glass annealing leer having a plurality of muffle heating chambers arranged zig-zag with respect to each other, a plurality of heating flues in the top wall of 95 each of said chambers, means for producing combustion for each of said flues, means common to all of said combustion producing means in the side wall of each of said chambers, and offtake means for each of said 100 flues, and means for connecting all of said offtakes together, substantially as described.

In testimony whereof, we have hereunto set our hands.

EDWIN E. MILNER.
WILLIAM J. LYTHE.
